DORSEY FROST ASBURY, OF WASHINGTON, DISTRICT OF COLUMBIA, ASSIGNOR
TO UNITED STATES ORDNANCE COMPANY, OF WASHINGTON, DISTRICT OF
COLUMBIA, A CORPORATION OF VIRGINIA.

PRIMER.

1,186,264.

Specification of Letters Patent.

Patented June 6, 1916.

Application filed July 13, 1915. Serial No. 39,593.

To all whom it may concern:

Be it known that I, DORSEY F. ASBURY, a citizen of the United States, and resident of the city of Washington, in the District of Columbia, have invented certain new and useful Improvements in Primers, of which the following is a specification.

My invention relates to primers and more particularly to plungers therefor.

10 In the construction of primers of the type used for igniting the charge in guns of large caliber there is embodied a plunger which is normally held in safe position with respect to the percussion cap by a shearing flange 15 formed integral therewith and abutting a shoulder formed on the plunger cup. In order to assure both the safety and correct operation of the primer this shearing flange must possess a predetermined thickness. If 20 this flange has less than the requisite thickness it will be sheared as a result of the inertia imparted to the plunger by shocks incident to the feeding of the primer to its seat in the mushroom stem or to the firing of 25 the gun and a premature explosion of the primer will follow. If this flange has more than the requisite thickness the blow of the firing hammer against the plunger will fail to shear the flange and a misfire of the 30 gun will result. In turning these plungers to shape it is difficult to produce the shearing flanges of a uniform and requisite thickness as a sharp cutting tool will result in a shearing flange of less than the requisite 35 thickness while a relatively dull tool will produce a shearing flange having too great a thickness to permit the correct operation of the primer, and in many instances a dull tool will also rupture or partly shear the flange 40 during turning.

It is therefore my purpose to provide a primer plunger embodying an improved construction whereby the defects and objections previously noted are obviated. To this end 45 I form the shearing member independently of the body of the plunger and then assemble the same therewith. By so constructing the shearing member I am enabled to utilize such method or methods of manufacture as 50 will assure the requisite thickness thereof necessary to the safety and correct operation of the primer.

In the drawings chosen for the purpose of illustrating my invention, the scope

whereof is pointed out in the claims; Figure 55 1 is a longitudinal section through a primer embodying a plunger constructed in accordance with my invention; Fig. 2, a longitudinal section through the plunger; Fig. 3, a section on the line 3—3 of Fig. 2; Fig. 4, 60 a longitudinal section through a plunger showing a modified form of my invention, and Fig. 5, a section on the line 5—5 of Fig. 4.

In the drawings A is the primer case 65 which is of tubular form and has one end of its bore reduced as at 10 to form a shoulder 11. Threaded in the case A is a plunger cup B which abuts the shoulder 11 and has seated therein a percussion cap C. 70

The improved plunger is indicated at D and is shown as comprising sections 12 and 13. One end of the section 12 is engaged in the reduced bore 10 whereby the plunger may be struck by the firing hammer of the 75 gun for the purpose of exploding the primer all in the usual and well known manner. The other end of the section 12 is provided with a recess 14 in which is fitted a reduced portion 15 of the section 13. The plunger 80 D carries a shearing member 16 preferably in the form of a washer. In assembling the shearing member is engaged over the reduced portion 15 and the latter then fitted in the recess 14 when the member 16 will 85 be clamped between the sections 12 and 13. It will be noted that the reduced portion 15 of the member 16 is slightly longer than the depth of the recess 14 so that when the sections 12 and 13 are interfitted a circumferential groove is formed in which the member 16 seats. The interior of the 90 plunger cup is provided with a shoulder 17 which is engaged by the member 16 whereby the plunger is normally held out of engagement with the cap C. When the plunger 95 D is struck by the hammer of the firing mechanism of the gun the member 16 is sheared and the plunger driven into engagement with the cap C to explode the primer. 100

In the modified form of my invention illustrated in Figs. 4 and 5 I provide the plunger with a circumferential groove 18 wherein is fitted a shearing member 19. This member 19 is in the form of a split 105 washer and is forced over the plunger at the groove 18 until the member is disposed concentric with the plunger when the ends

of the member will slightly contract to secure same in proper assembled relation.

I preferably form the shearing members 16 and 19 by stamping or pressing although any other method of manufacture may be employed that will assure the requisite thickness thereof essential to the safety and correct operation of the primer. By making the shearing members from rolled sheets, a homogeneous material is used and consequently uniform shearing resistance is assured.

What I claim and desire to secure by Letters Patent is:

A primer comprising a casing, a plunger 15 cup therein provided with an interior shoulder, a percussion cap in said cup, a plunger, and a shearing member formed independently of and carried by the plunger and normally engaging said shoulder to hold 20 the plunger against firing movement with respect to the cap.

In testimony whereof, I affix my signature, in the presence of two witnesses.

DORSEY FROST ASBURY.
